UNITED STATES PATENT OFFICE.

ALBERT H. ARMSTRONG, OF SCHENECTADY, NEW YORK, ASSIGNOR TO THE GENERAL ELECTRIC COMPANY, OF NEW YORK.

ELECTRIC-RAILWAY SYSTEM.

SPECIFICATION forming part of Letters Patent No. 650,364, dated May 29, 1900.

Application filed April 8, 1899. Serial No. 712,212. (No model.)

To all whom it may concern:

Be it known that I, ALBERT H. ARMSTRONG, a citizen of the United States, residing at Schenectady, county of Schenectady, State of New York, have invented certain new and useful Improvements in Electric-Railway Systems, (Case No. 1,062,) of which the following is a specification.

In supplying current to third-rail or other electric-railway systems equipped with alternating-current motors it has been proposed to use a central generating-station producing multiphase current of high tension and to transmit this current to various step-down transformers along the line of the road and to connect the secondaries of each transformer or set of transformers to supply-conductors comprising the track-rails and one or more third rails or trolley-wires. Third rails are in general preferable, as railways which it is proposed to operate by alternating current are usually long-distance high-speed roads owning their own right of way. In any case this arrangement involves either an enormous number of transformers or the transmission of current to the motors through a considerable length of supply-conductor. With the preferred construction—two iron third rails in two sides of a three-phase or two-phase system and the two track-rails in multiple in the other side—each car will receive current on the average through a heavy iron conductor in each leg of the circuit of a length equal to about one-quarter of the distance between transformers, while in some positions the path through iron will be equal to half the distance between transformers for each leg of the circuit.

Now alternating-current railways commonly employ induction-motors, which themselves have more or less self-induction and which are particularly sensitive to self-induction in the line. The passage of the low-tension alternating currents, necessarily of some considerable volume, through any considerable length of iron conductor produces an inductive drop such as to sometimes practically wipe out the impressed voltage as the car starts and in all cases to seriously interfere with the operation of the motors. The sup-

ply-conductors, therefore, when constructed of iron or other magnetic material constitute an inductive conducting system which seriously interferes with the proper working of the motors. This difficulty may be corrected by the use of a large number of transformers connected at frequent intervals; but this arrangement is very expensive and introduces large losses, due to the magnetizing-current, &c., of the transformer, so that in practice it cannot be carried very far. Even if third rails of copper or other non-magnetic material or trolley-wires sufficiently heavy to carry the large currents needed should be employed there would still be an inductive drop in the track-rails, which would with this arrangement seriously unbalance the system. Obviously each transformer in the system above set forth may be replaced by a generating-station, an "inverted rotary," or any other source of alternating current; but the difficulties above set forth will still persist, usually in an even greater degree. I am able to avoid these troubles by employing only a reasonable number of sources of current and connecting each of them to the track-rails and to the third rails or, speaking more generally, to the inductive conductors at a number of different points by heavy leads of copper or other non-magnetic conducting metal, constituting a substantially-non-inductive system. These conductors are preferably arranged in a triple non-inductive cable. In my improved system in its best form I use one or more multiphase generating-stations, leads or feeders extending therefrom, a reasonable number of step-down transformers in multiple from the leads, and iron or steel conductors (which are best adapted to withstand heavy strains and rough usage) connected to the secondaries of the transformer by non-inductive cables, each secondary feeding the line at a number of different points. In this way I may use only a limited number of transformers, sufficient for the most economical distribution, first cost and losses being considered, and yet reduce the maximum inductive path through which current must pass to a minimum.

In the drawings attached to this specification, Figure 1 is a diagram of a railway sys-

tem or a portion thereof embodying my invention, and Fig. 2 is a cross-section of a triple cable.

Referring more particularly to Fig. 1, A is 5 a generator or generator-station capable of supplying three-phase currents to the lines B' B² B³. I have shown in this application three-phase currents, since they are particularly well adapted to railway-work; but obviously single-phase currents, two-phase currents, or any other desired alternating currents may be employed.

C C are the track-rails of a railway system, and D' D² are the third rails or conductors, 15 extending along the line of the road. In order to supply current to the third rails D' D² and to the track-rails C C, I carry the conductors B' B² B³ substantially the whole length of the railway and connect these conductors by 20 feeders or otherwise to points at which I wish to locate the transformers T' T² T³, &c. Each of these transformers is here shown as of the open-delta type; but obviously three transformers connected in Y or in delta or with their 25 primaries in Y and their secondaries in delta or arranged in any other way to transform the particular currents employed may be used in place of each of the transformers T' T² T³. The primaries of these transformers are supplied, as shown, from the generator A through 30 the lines B' B² B³. The secondaries are each connected at a plurality of points to the third rails D' and D² and to the track-rails C. As the best and simplest way of accomplishing 35 this result I carry along the line of the road three heavy conductors of non-magnetic metal E' E² E³. These conductors are preferably arranged in a triple cable, as shown in Fig. 2, in order to reduce their inductance as 40 much as possible. This cable is connected to the secondary of each of the transformers T' T² T³ and is also connected to the track-rails C C and to the third rails D' D² at a number of points of conductors F F F. In this way 45 I am enabled to supply current to the car

irrespective of where it may be located on the road in such a way that no considerable reactive electromotive force shall be created outside of the motor itself.

What I claim as new, and desire to secure 50 by Letters Patent of the United States, is—

1. In combination, in an alternating-current electric-railway system, supply-conductors, constituting an inductive conducting system, a plurality of sources of alternating-current supply arranged at intervals along the railway, and a substantially-non-inductive system of conductors connecting each of said sources to a plurality of points on the supply-conductors. 55

2. In combination, in an alternating-current electric-railway system, supply-conductors constituting an inductive conducting system, and comprising track-rails of magnetic material, a substantially-non-inductive system of conductors extending along the railway, a plurality of sources of alternating-current supply arranged at intervals along the road and connected to said non-inductive system and more numerous connections between 70 said non-inductive system and said supply-conductors. 60

3. In combination, a generator of alternating currents, a plurality of transformers supplied in multiple arc therefrom, an electric 75 railway adapted to be operated by alternating currents, iron or steel supply-conductors for said railway, a non-inductive or substantially-non-inductive system of conductors extending along the line of the road, electrical 80 connections from the secondary of each of the transformers of said non-inductive system, and more numerous connections between said system and said supply-conductors. 85

In witness whereof I have hereunto set my hand this 6th day of April, 1899.

ALBERT H. ARMSTRONG.
